LOCK FOR RAILWAY-SPIKES.

1,122,373.

Specification of Letters Patent.

Patented Dec. 29, 1914.

Application filed April 27, 1914. Serial No. 834,791.

To all whom it may concern:

Be it known that I, FRANK DUTCHER, a citizen of the United States, residing at Versailles, in the county of Allegheny and 5 State of Pennsylvania, have invented certain new and useful Improvements in Locks for Railway-Spikes, of which the following is a specification, reference being had therein to the accompanying drawing.

10 This invention relates to improvements in locks for railway spikes and the primary object of the invention is to provide a simple, efficient and comparatively inexpensive lock for the spikes used in holding rail-

15 road-rails in position.

It is well-known to railroad men that the spikes used to hold the rails in position work so loose that they lose their efficiency and unless they are carefully watched, they 20 will, in some instances, work entirely out of the tie. This is due probably to the fact that the rails have a downward movement compressing into the ties and to prevent this, it is common to use a plate under the 25 rail which I will term a bed plate. This relieves, to some extent, the compressing of the rail, but even with these bed plates, the passage of heavy trains in time press even the bed plates somewhat into the ties 30 so that the passing of a train depresses the rail and this can be observed by a person watching the rails when a train is passing thereover. This spring movement seems to be especially noticeable at the joints of the 35 rail, and this vertical vibration of the rail in time will work the spikes loose and lose their efficiency to such an extent as to become dangerous. By reason of this, it is one of the duties of the "track-walkers" to 40 see that the spikes are kept in place and for this purpose they carry with them a suitable implement for driving the spike back to position when they find one that has worked loose. The springing of the rails is con- 45 sidered desirable in thus providing an elastic road bed.

One of the primary objects of my invention is to provide a lock for the spikes by utilizing the bed plate, and so constructing 50 the lock that the bed plate may have the vertical movement with the rail independent of the spike, and without effecting the locking action while, at the same time the lock will prevent the spike from being with-

drawn from its original position; the lock 55 being in such form and nature that the spike can be withdrawn when desired for the purpose of putting in a new tie; a new rail or for any other reason.

In the accompanying drawings:—Figure 60 1 is a perspective view of a railroad-rail, its tie, the spikes, and the bed plate with my improved locking element formed directly from the bed plate. Fig. 2 is a cross sectional view showing the spike at the left of 65 the figure driven to position and the lock in its locking position, while the lock at the right-hand side of the figure is in its un-locking position and the spike in the act of being driven into the tie. Fig. 3 is an en- 70 larged sectional view showing the spike in its driven position and the lock in its locking position. Fig. 4 is a large view of a spike showing a slight modification of the 75 application of the invention. Fig. 5 is a plan view showing a modification in the form of the lock.

Referring now to the drawings in which like reference numerals designate similar parts, 1 is a railroad-rail, 2 a tie, 3 the spike 80 and 4 the bed plate. In Figs. 2 and 3 is shown a recess 5 as illustrating the depression which the bed plate 4 often makes in the tie, permitting the rail to spring down and often times the foundation for the tie 85 itself will permit the depression of the tie which causes the rail to be depressed or sprung down when a train is passing over it, and these vertical movements provide what is often referred to as an elastic road bed. 90 In either event the vertical movements are liable to cause the spike to work loose and pulling the spike out of the tie to such an extent that its efficiency is lessened, making the situation to say the least undesirable and 95 often times dangerous for passing trains and especially at the abutting ends of the rails.

The bed plates 4 are provided with openings 6 through which the spike is driven. 100 My improvement consists in making the outer wall of each of the openings 6 into a locking lip 7 by slitting the bed plate outwardly as shown at 8. These locking lips 7 are bent slightly upwardly or outwardly as 105 shown, and normally assume the position shown at the right side of Fig. 2, so that the spike can be freely driven through the

opening in the plate 4. When the spike has been driven to the position shown in Fig. 3 and at the left side of Fig. 2 then the locking lip 7 is slightly tapped or knocked 5 downwardly to cause its lower edge 9 to bite into the outer side of the spike. These bed plates 4 are made of sheet iron usually approximately an eighth of an inch or more in thickness so that the short locking lips 7 are 10 very stiff. When they are knocked down into the position shown in Fig. 3, they are sufficiently stiff to remain in that position with their lower edges 9 biting into the spikes. When a movement arises between 15 the plate 4 and the tie 2 such as when a recess is worn therein, then the locking lip 7 is carried down with the plate and it cuts into the spike a very slight groove 10, scraping or cutting a thin shaving from the spike 20 which will accumulate at the bottom in a manner somewhat as shown at 11 Fig. 3. In this way an elongated slot is formed in the outer face of the spike and the plate 4 may move up and down independent of the spike, 25 but the spike can not work out because the shoulder 11 will prevent it from passing by the locking lip 7. The groove 5 here shown is probably exaggerated from actual service, but there is a slight movement due probably 30 to the elasticity of the tie itself even where there is little or no perceptible recess formed. But there is a movement and this movement must be provided for in any efficient spike lock. When it is desired to withdraw 35 the spike, the locking lip can be forced upwardly slightly by driving a suitable tool under its projecting edge, or a powerful crow-bar would pull the spike up against the lip, and if the lip had been driven sufficiently far into the spike to form a shoulder 40 sufficiently strong, the lip would be sprung upwardly to permit the spike to be removed. On the other hand, if the lip has not been deeply driven into the spike, the crow-bar 45 would draw the spike out with the lips scraping a small portion of the spike away as it is being withdrawn.

From the foregoing, it will be observed that my improvement contemplates the formation 50 in the spike of a groove which is relatively elongated in respect to the locking edge of the lip 7 to provide for a movement of the bed plate independent of the spike. I prefer to form this elongated 55 groove in the spike by the downward movement of the plate itself because then the ordinary spike can be used. However, I wish it understood that a very slight elongated groove can be formed in the spike 60 when it is manufactured as shown at 12 in Fig. 4, and in that event, the locking lip would simply be adapted to bring its locking edge within this groove and the plate 4 and its lock is capable of a movement independent 65 of the spike and yet the spike

is prevented from working out by reason of the lock extending into the groove 12 of the spike. Again, instead of having the locking lip 7 constructed to bite into the whole face of the spike, it can be constructed as shown 70 in Fig. 5 with the angular edges 7a which will engage only the corners of the spike and bite into the corners.

From the foregoing, it will be observed that my improved lock for spikes will not 75 add any to the expense of a sheet metal bed plate, because the die in punching the opening 6 will at the same time punch out the slits 8 and bend the lip 7.

I wish it to be also understood that the 80 locking lip 7 may be constructed so that it can be forced down in a line or in a plane with the bed plate, or even may be carried on and inclined downwardly instead of upwardly if it should be desired to more positively 85 lock the spike; the inventive idea being the utilization of one wall of the spike opening as a locking lip that may be forced into arrangement with the spike. If the locking lip should incline downwardly, then 90 the plate would primarily be supported slightly above the tie until the spike was driven down and caused to draw or force downwardly the rail and the plate which would then cause the downwardly inclined 95 lip to be forced upward into arrangement with the spike.

Having thus described my invention what I claim and desire to secure by Letters Patent is:

1. A lock for spikes comprising a bed plate having a spike opening, one wall of the opening normally extending upward and adapted to be moved downward into contact with the face of the spike for the purpose described.

2. An improved lock for railway spikes comprising a bed plate having a spike opening, one wall of the opening formed by a normally inwardly and upwardly extending locking lip adapted to be pressed down into contact with the face of the spike.

3. An improved lock for railway spikes comprising a bed plate having a spike opening, the outer wall of the opening formed by an independent normally upwardly and inwardly extending locking lip adapted to be forced downwardly to cause its inner lower edge to bite into the surface of the spike for the purpose described.

4. An improved railway spike lock comprising a bed plate having a spike opening, the outer wall of the opening formed into the vertical movable locking lip, a spike having an elongated groove in its outer portion, said locking lip extending into the said elongated groove of the spike.

5. An improved railway spike lock comprising a bed plate having a spike opening, one wall of the bed plate formed into a

vertically movable lip, the inner edge of the lip having angular portions to engage the corners of the spike for the purpose described.

5 6. An improved railway spike lock comprising a bed plate having a spike opening, one wall of the opening comprising a vertically movable locking lip adapted to have its inner edge bite into the spike and form a 10 groove therein by the movement of the bed plate independent of the spike for the purpose described.

15 7. An improved railway spike lock comprising a bed plate having a spike opening, one wall of the opening comprising a vertically movable locking lip, a spike having its head provided with a shoulder adapted to engage the said locking lip and carrying it

downward to assume a locking position in engagement with the spike.

8. An improved railway spike lock comprising a bed plate having a spike opening, one wall of the opening having an inwardly projecting locking lip, the inner end of the lip normally extending inwardly and upwardly, and a spike having its head provided with a shoulder to engage the inner end of the locking lip and force it downward into locking position when the spike is driven down.

20 In testimony whereof I hereunto affix my signature in the presence of two witnesses.

FRANK DUTCHER.
